UNITED STATES PATENT OFFICE.

EVERETT B. HUGHES, OF NORTH VERNON, INDIANA.

BANK-VAULT.

1,326,058.

Specification of Letters Patent. Patented Dec. 23, 1919.

Application filed May 26, 1919. Serial No. 299,864.

To all whom it may concern:

Be it known that I, EVERETT B. HUGHES, a citizen of the United States, residing at North Vernon, in the county of Jennings 5 and State of Indiana, have invented new and useful Improvements in Bank-Vaults, of which the following is a specification.

This invention relates to the construction of bank vaults, and the object is to provide 10 a wall which can not be penetrated by the oxy-acetylene flame.

A further object is to provide a wall or door construction which shall consist of an outer layer of case-hardened, or so-called 15 drill-proof steel, an adjacent layer of soft steel which will be melted if subjected to the oxy-acetylene flame, and portions of which when fused will flow into the apertures formed in the outer layer of steel, in the 20 event that the latter is penetrated by a drill, or by the use of the means above referred to.

A still further object is to provide a construction of the type indicated, and to form in connection therewith a third layer of fire 25 brick in which is embedded wire mesh formed of case-hardened steel wire, this layer last named to be provided with apertures for the purpose specified below.

A fourth layer constituting an inner layer 30 may be used as a retainer for the layer of fire brick.

With the foregoing and other objects in view, the invention consists in the novel construction, combination, and arrangement of 35 elements hereinafter described and claimed.

In the drawings,

Figure 1 is a view in elevation of a vault, with parts broken away, and with a portion of the side wall in section.

40 Fig. 2 is a fragmentary view, in section, of the wall construction.

In carrying out my invention I provide an outer layer designated 10 formed of case-hardened steel, or so-called drill-proof steel. 45 This layer may be one quarter of an inch thick, the thickness however depending upon circumstances.

A second layer 12 is formed of soft steel which may be fused when subjected to the 50 oxy-acetylene flame, and when so fused, portions will flow into the aperture or apertures formed in the outer layer 10, in the event that the latter is penetrated.

A third layer 14 consists of fire brick, and within this layer there is embedded a wire 55 mesh constructed of case-hardened steel wire of approximately three-fourths inch mesh. This layer should be of a suitable thickness, and the layer is perforated, the apertures therein being filled with sulfur. The apertures are designated 15 and the filling thereof is shown at 16. The layer 14 may also be coated with sulfur on both sides. That portion of the sulfur which is placed within the apertures is mixed with gun powder, or 60 other explosive. The burning sulfur on the surface of the layer will give off fumes of a suffocating nature, and the charge within each small aperture will cause a slight explosion sufficient to drive small particles against 65 the hand or face of the individual endeavoring to obtain entrance to the vault. These marks will serve for purposes of identification.

A fourth layer designated 18 serves as a 75 retainer for the layer of fire brick just described. It is the intention that the apertures in layer 14 shall extend only part way through the layer.

The construction described is to be employed in building all of the walls of the 80 vault, and also in building the door.

What is claimed is—

1. In a wall construction for bank vaults, an outer layer of hardened steel, an adjacent 85 layer of soft steel, a third layer of fire brick with wire mesh embedded therein, and a coating of a fume generating substance for one of said layers.

2. In a wall and door construction for bank vaults, an outer layer of hardened steel, an adjacent layer of soft steel, a third layer of refractory material, the third layer being provided with apertures, and charges within the apertures, formed of explosive 95 material.

3. In a wall and door construction for bank vaults, an outer layer of hardened steel, an adjacent layer of soft steel, a third layer provided with apertures and including 100 a reinforcing element, a coating of a fume-generating substance for the third layer, and charges of explosive material within the apertures.

In testimony whereof I affix my signature. 105
EVERETT B. HUGHES.
